[57] **CLAIM**

The ornamental design for eyeglasses with extended vision optical elements, as shown and described.

DESCRIPTION

FIG. 1 is a perspective view showing the top, rear and sides of eyeglasses with a pair of extended vision optical elements in non-operable stored positions, showing our new design, the side opposite being a mirror image;

FIG. 2 is a perspective view showing the top, front and sides of the eyeglasses with a right side optical element in an operable position; and,

FIG. 3 is a perspective view showing the rear and sides of the eyeglasses with a left operable element in an operable position.
